SPRAY NOZZLE

Horace A. Cartwright, Minneapolis, Minn.

Application November 22, 1950, Serial No. 197,025

11 Claims. (Cl. 299—139)

1

This invention relates to spray nozzles. More particularly, it relates to spray nozzles constructed and arranged for the application of liquids of a rather viscous nature to relatively flat surfaces such as roads.

In the distribution of liquids of a viscous nature, and especially in road building, it is highly important that the liquid be distributed uniformly and at the proper rate in order to form a smooth, even surface substantially free of overlaps, skips, and heavy spots. It is also important, if at all possible, in order to facilitate the application of such materials and thereby accomplish the same with a maximum of efficiency and a minimum of time consumption, that the start and finish lines extend transversely to the direction of the spraying operation, and that these finish lines form a straight line.

In the past, it has been found to be advantageous in the application of such materials in order to prevent skips and heavy spots and thus insure a uniform application, to apply such materials by arranging the spray nozzles through which the material is forced so as to form staggered spray fans and thus avoid interference of the fans with each other. These staggered spray fans are considered staggered in that the respective fans are oriented parallel to each other, but at an angle to the direction of the spraying operation. Thus it is possible to have each spray nozzle overlap one-half the area covered by its two adjacent nozzles and thereby insure an even application of the viscous material. The difficulty with such an arrangement, however, is that the starting and finishing lines formed as a result of this orientation of the spray fans, have always presented a jagged outline in contrast to what is desired, namely, a straight line. This is especially annoying when it is necessary to finish the application of the materials against the side of a sidewalk or curb. My invention is directed towards the elimination of such jagged finish lines.

A general object of my invention is to provide a novel and improved spray nozzle of cheap and simple construction and of improved efficiency.

A more specific object is to provide a spray nozzle capable of producing a straight starting and finishing line which is normal to the direction of the spraying operation.

Another object is to provide a spray nozzle capable of being mounted and arranged on a transverse spray bar to form, in conjunction with similar spray nozzles, a plurality of staggered spray fans to permit the even application

2

of a viscous fluid thereby, and nevertheless being capable of forming a straight starting or finishing line normal to the direction of the spraying operation as a result of the flow being shut off or turned on by these nozzles.

A further object is to provide a spray nozzle capable of forming a straight starting or finishing line arranged transversely with respect to the direction of the spraying operation and at the same time capable of forming such a line without an excessive application of the viscous material along that line.

These and other objects and advantages of my invention will more fully appear from the following description made in connection with the accompanying drawings wherein like reference characters refer to the same or similar parts throughout the several views and in which:

Figure 1 is an exploded view of one embodiment of my invention.

Figure 2 is a vertical sectional view taken along line 2—2 of Figure 1.

Figure 3 is a vertical, sectional view taken along line 3—3 of Figure 2.

Figure 4 is a vertical sectional view taken along line 4—4 of Figure 3.

Figure 5 is a bottom plan view of a plurality of spray nozzles embodying my invention shown in open position and forming staggered and overlapping spray fans.

Figure 6 is a bottom plan view of one embodiment of my invention approaching closed position.

Figure 7 is a bottom plan view of a similar embodiment of my invention disposed in closed position.

Figure 8 is a diagrammatical view of the finish line normally formed by spray bars wherein overlapping spray fans have been utilized.

Figure 9 is a diagrammatical view showing the more desirable starting and finishing lines formed by one embodiment of my invention and showing the manner in which the spray fans swing to form such a straight line.

One embodiment of my invention may include, as shown in Figures 1—7, a head 10, one end portion of which is shaped to form a disc 11 and the other end portion of which is formed into a conduit 12, the outer end of which has external threads 13 as shown in Figure 1. These threads 13 are of equal pitch and depth with respect to internal threads which are formed in apertures 14 of the spray bar 15. These apertures 14 are spaced regularly along the length of the spray bar 15, and the spray bar is normally arranged

50

transversely with respect to the direction of the spraying operation, indicated by an arrow in Figure 5. The conduit portion 12 has a passage 16 which extends therethrough and terminates at the flat lower surface 17 of the disc 11. This passage 16 is disposed centrally of the conduit portion 12 and terminates centrally with respect thereto at a point slightly inward from the periphery of the disc 11. Formed through the center of the disc 11 is a centrally disposed and internally threaded aperture 18 which extends vertically through the disc.

A control member 19 having a flat upper face 20 is secured beneath the disc 11 with the two faces held in flat registering relation by means of a compression bolt 21 which extends upwardly through a central aperture 22 formed within the control member 19. The bolt 21 has external threads 23 which cooperate with the internal threads of the passage 18 to hold the head 19 and the control member 19 in compressed relation. A compression-type spring 24 is carried by the bolt 21 to constantly urge the two flat surfaces, 17 and 20, toward each other.

The control member 19 has a lever arm 25 extending outwardly and radially therefrom. An aperture 26 is formed in the outer end of the lever arm 25 to receive a bolt or rivet 27 which connects the same to a gang control bar 28 as best shown in Figure 5.

Formed in the lower surface of the control member 19 is a milled spray slot 29 which has vertical side walls 30 and arcuately shaped end walls 31 as best shown in Figure 3. This milled slot 29 communicates with the upper surface 20 of the control member 19 by means of a short fluid passage 32. This short fluid passage 32 extends vertically from the upper portion of the spray slot 29 to the upper surface 20 and is disposed centrally with respect to the length of the slot 29. The slot 29 is arranged obliquely with respect to the radius of the control member or disc 19 and the fluid passage 32 is arranged so as to communicate with the passage 16 when the control member 19 is moved to open position. A small portion of the metal material of the upper surface 20 surrounding the passage 32 is dished out as best shown in Figure 1 and Figure 4.

To assemble my spray nozzle, the bolt 21 is inserted through the spring 24 and through the aperture 22 of the control member 19 from below and then threaded into the aperture 18 of the head 10. By tightening the bolt 21, the head 10 and the control member 19 are compressed tightly together so that the two flat surfaces 17 and 20 will register in close tight-fitting relation to prevent escape of any of the fluid which may be forced through the passage 16. Thereafter, each of the nozzles is mounted on the spray bar 15 as best shown in Figure 5 and connected to the gang control bar 28. Each of the apertures 14 in the spray bar 15 are carefully formed so as to extend normal to the length of the spray bar. When the gang control bar is moved so that each of the slots 29 of the control member 19 has been moved to open position with respect to the passage 16, the spray fan will emanate from each of the slots in staggered relation with respect to each other. Actually, the spray fans will be parallel, but each will be oriented at an angle to the direction of the spraying operation.

In operation, the respective spray slots of each nozzle will cause the spray fans to spread below the same in staggered and overlapping relation, as best shown in Figure 5. This relation has been

found to be highly desirable in applying an even layer of such viscous materials, but no previously known spraying mechanism constructed to apply such materials in this manner could form a straight finish line. All previously known spraying mechanism, when arranged to provide staggered spray fans, terminate the spraying operation with a jagged finish line such as is shown in Figure 8. However, with a spray bar having nozzles constructed in accordance with my invention, the starting and finishing line is straight. As the control bar 28 is swung toward partially closed position as shown in Figure 6, the amount of viscous material which can be forced outwardly through the passage 16 is considerably diminished. At the same time, the slot is thus swung to a position normal to the direction of the spraying operation as shown in Figure 6. The swinging of the spray slot 29 to a position normal with respect to the direction of the spraying operation will cause the spray fan to be swung accordingly, and to form, in conjunction with the other spray nozzles, a straight finish line such as is shown in Figure 9. Because the amount of viscous material which can be forced through the nozzle has been reduced by the swinging of the control member to the position shown in Figure 6, there will be no heavy spots formed along the finish line and thus there will be no running of the viscous material across the surface being sprayed.

When the operator of the spraying machine wishes to commence the spraying operation, the gang control bar 28 is swung so as to move the control members 19 to the open position shown in Figure 5. The starting line, which is formed as a result of the opening of the control member, will be a straight line such as shown in Figure 9, since the spray fans, which will be formed when the control members 19 move toward open position, will swing in the reverse of the manner described above. In other words, a straight starting line will be formed, and immediately thereafter the spray fans will swing from a transverse position with respect to the direction of the spraying operation to an obliquely angled position such as is shown in Figure 5.

Figure 7 shows the position of the control member 19 and the spray slot 29 when the control member has been moved to closed position. The spray slot 29 is then oriented at an angle to the direction of the spraying operation. At first glance it might appear that the finish line would, as a result of the closed position of the spray slot 29, be formed at an angle to the direction of the spraying operation. This is not the case, however, since the action through which the control members 19 are moved from open to closed position or vice versa, is a fairly rapid action and this rapid action, coupled with the viscous nature of the spray materials, will cause the finish line to be oriented normal to the direction of the spraying operation. In other words, the spray fan will normally be cut off approximately at the time the spray slot 29 reaches the position shown in Figure 6.

Thus it can be seen that I have provided a spray nozzle constructed to facilitate spraying operations adjacent curbs, sidewalks, etc. where a straight finish line or starting line is imperative. Moreover, a plurality of spray nozzles constructed in accordance with my invention can be operated in the conventional and highly desirable relation wherein they are disposed to provide staggered spray fans which overlap each

other and yet are capable of forming a straight starting and finishing line which is normal to the direction of the spraying operation.

It should be noted that a spray bar equipped with a plurality of nozzles constructed in accordance with my invention and arranged as shown herein is capable, not only of forming a straight starting and finishing line, but is also capable of forming such a line without permitting an excessive application of the viscous material along that line.

It will, of course, be understood that various changes may be made in the form, details, arrangement and proportions of the parts without departing from the scope of my invention.

What I claim is:

1. A spray nozzle comprising a body having a feed passage with an inlet and an outlet formed therein, said body being adapted to be mounted on a spray bar or the like to connect said passage with a fluid source, and a rotating member secured to said body in tight fitting relation across said outlet and having a substantially flat outer surface, said rotating member having an elongated vertically side-walled slot the central portion only of which registers with the outlet of said feed passage in open position, said slot forming at its central portion only a passage through said rotating member and directing fluid forced through said passages into a spray fan formation.

2. A spray nozzle comprising a pair of non-porous bodies having opposed flat registering surfaces and being held tightly together for rotation with respect to each other, one of said bodies having a passage with an inlet and an outlet extending therethrough and being adapted to have the inlet of said passage connected to a fluid source, and the other of said bodies having an elongated slot with curved end walls formed therein and positioned eccentrically and communicating directly with the outlet of said passage with its central portion only when said other body is disposed in open position with respect to said outlet, said slot forming into a spray fan any liquid forced under pressure through said outlet and said slot while in open position to cause the liquid to be sprayed along a substantially straight line.

3. A spray nozzle comprising a pair of non-porous bodies having opposed flat registering surfaces and being tightly connected together for rotation with respect to each other, one of said bodies having a passage with an inlet and an outlet extending therethrough and being adapted to have the inlet of said passage connected to a fluid source, and the other of said bodies having an elongated eccentrically disposed straight slot formed in its outer surface and communicating first via its central portion with the outlet of said passage when said other body is disposed in open position with respect to said first mentioned body, said slot having vertical side walls and being disposed obliquely to the direction of the spraying operation when in open position and being disposed at substantially right angles to the direction of the spraying operation when approaching closed position whereby the spray fan normally formed by said slot in a fluid being forced under pressure through said passage and outwardly through said slot, will be caused to swing to a position substantially perpendicular to the direction of the spraying operation when said other body is moved to closed position and to thereby form a straight finish line when the spraying operation is terminated.

4. The structure defined in claim 2, said bodies being arranged for rotation on a common axis.

5. A spray nozzle comprising a pair of non-porous discs having opposed flat registering surfaces and being tightly connected together for rotation with respect to each other, one of said discs having a passage with an inlet and an outlet extending therethrough and being adapted to have the inlet of said passage connected to a fluid source, and the other of said discs having a substantially vertical slot formed in its non-registering flat surface and extending through said disc at a point centrally of the length of said slot to communicate with the outlet of said passage when said other disc is rotated to open position with respect to said outlet, said slot having straight side walls and being disposed obliquely to the direction of the spraying operation when in open position and being disposed substantially normal to the direction of the spraying operation when approaching closed position whereby the spray fan normally formed by a fluid being forced under pressure through said passage and outwardly through said slot may be caused to swing to a position substantially normal to the direction of the spraying operation when said other disc is moved to closed position and to thereby form a straight finish line when the spraying operation is terminated.

6. A spray nozzle comprising a pair of discs having opposed flat registering surfaces, means for connecting said discs together tightly for rotation with respect to each other, one of said discs having a passage with an inlet and an outlet extending therethrough and being adapted to have the inlet of said passage connected to a fluid source, and the other of said discs having a straight slot formed in its non-registering surface with substantially vertical straight side walls spaced apart a distance less than the diameter of said outlet, said slotted dish being swingable to either open or closed position, said slot being arranged to communicate via its longitudinal central portion with the outlet of said passage when said other disc is rotated to open position with respect to said first mentioned disc, said slot being disposed obliquely to the direction of the spraying operation when in open position and being disposed substantially normal to the direction of the spraying operation when approaching closed position whereby the spray fan normally formed by a fluid forced under pressure through said passage and outwardly through said slot, will be caused to swing to a position substantially normal to the direction of the spraying operation when said other disc is moved to closed position and to thereby form a straight finish line when the spraying operation is terminated.

7. A spray nozzle comprising a pair of bodies having opposed flat registering surfaces and being tightly connected together for rotation with respect to each other, one of said bodies having a passage with an inlet and an outlet extending therethrough, and being adapted to have the inlet of said passage connected to a fluid source and the other of said bodies having an upright straight slot formed in its outer surface and communicating with the outlet of said passage when said other body is disposed in open position with respect to said first mentioned body, said communication being established by an orifice formed in the flat registering surface of said second mentioned body and centrally of the length of said slot, said orifice being substantially equal in diameter to the diameter of said outlet and

being centrally disposed with respect to the upper portion of said slot, said slotted body being swingable to open and closed position, said slot being disposed obliquely to the direction of the spraying operation when in open position and being disposed substantially normal to the direction of the spraying operation when approaching closed position whereby the spray fan normally formed by fluid being forced under pressure through said passage and outwardly through said slot will be caused by said slot to swing to a position substantially normal to the direction of the spraying operation when said body is moved to closed position and to thereby form a straight finish line when the spraying operation is terminated.

8. A spray nozzle comprising a pair of non-porous bodies having opposed flat registering surfaces and being tightly connected together for rotation with respect to each other, one of said bodies having a passage with an inlet and an outlet extending therethrough and being adapted to have the inlet of said passage connected to a fluid source, and the other of said bodies having a straight slot with straight and parallel vertical side walls formed therein and communicating at its central portion taken longitudinally with the outlet of said passage when said other body is disposed in open position with respect to said first mentioned body, said slot being disposed obliquely to the direction of the spraying operation when in open position and being disposed substantially normal to the direction of the spraying operation when approaching closed position whereby the spray fan normally formed by a fluid being forced under pressure through said passage and outwardly through said slot, will be caused by said slot to swing to a position substantially normal to the direction of the spraying operation when said other body is moved toward closed position and to thereby form a straight finish line when the spraying operation is terminated.

9. A spray nozzle comprising a pair of non-porous bodies having opposed flat registering surfaces and being tightly connected together for rotation with respect to each other, one of said bodies having a passage with an inlet and an outlet extending therethrough and being adapted to have the inlet of said passage connected to a fluid source, and the other of said bodies having a flat non-registering surface with a straight slot formed therein communicating centrally of its length with the outlet of said passage when said other body is disposed in open position with respect to said first mentioned body, said slot having vertical and straight side walls and being substantially greater in length than the diameter of said outlet, said slot being disposed obliquely to the direction of the spraying operation when in open position and being disposed substantially normal to the direction of the spraying operation when approaching closed position whereby the spray fan normally formed by said slot in a fluid being forced under pressure through said passage and outwardly through said slot will be caused to swing to a position substantially normal to the direction of the spraying operation when said other body is moved to closed position and to thereby form, when arranged transversely with respect to the direction of the spraying operation with a plurality of similarly constructed spray nozzles, a straight finish line as the spraying operation is terminated.

10. A spray nozzle comprising a pair of discs

5 having opposed flat registering surfaces, means for tightly connecting said discs together for rotation on a common axis, one of said discs having a passage with an inlet and an outlet extending therethrough and being adapted to be mounted on a spray bar to connect said inlet with a fluid source, and the other of said discs having a vertically side-walled straight slot formed therein and communicating midway its 10 length with the outlet of said passage when said other disc is disposed in open position with respect to said first mentioned disc, said communication being accomplished by an orifice extending downwardly from the flat registering surface 15 of said other disc to the medial longitudinal portion of said slot, said orifice being disposed centrally of said slot and communicating with the upper portion thereof, the side walls of said slot being straight and spaced a distance apart less 20 than the diameter of said outlet, said slot being greater in length than the diameter of said outlet and being arranged so as to be disposed obliquely to the direction of the spraying operation when in open position and to be disposed 25 substantially normal to the direction of the spraying operation when approaching closed position, whereby the spray fan normally formed by said slot in a fluid being forced under pressure through said passage and outwardly through said slot, will be caused to swing to a position substantially normal to the direction of the spraying operation when said other body is moved toward closed position and to thereby form a straight finish line as the spraying operation is terminated.

35 11. A spray nozzle comprising a pair of non-porous bodies having opposed surfaces held together for rotation relative to each other, one of said bodies having a passage with an inlet and 40 an outlet extending therethrough and being adapted to have the inlet of said passage connected to a fluid source, the other of said bodies having a straight slot formed therein and communicating with the outlet of said passage when 45 said other body is disposed in open position with respect to said first mentioned body, said slot being disposed obliquely to the direction of the spraying operation when in open position and being disposed at substantially right angles to 50 the direction of the spraying operation when approaching closed position whereby the spray fan normally formed by said slot in a fluid being forced under pressure through said passage and outwardly through said slot will be caused to 55 swing to a position substantially perpendicular to the direction of the spraying operation when said other body is moved to closed position and to thereby form a straight finish line when the spraying operation is terminated.
